STOCK QUOTATION PROJECTING MACHINE

August D. Eitzen, Rockville Centre, N. Y., assignor
to News Projection Corporation, New York,
N. Y., a corporation of New York

Application February 18, 1932, Serial No. 593,768
Renewed August 20, 1936

10 Claims. (Cl. 271—2.3)

This invention relates to stock quotation projecting machines in general and more especially to stock quotation projecting machines in which the motive power is running constantly and the tape pulling action only effective intermittently when the ticker operates.

Among the objects of the present invention, it is aimed to provide an improved stock quotation projecting machine including a tape feeding mechanism which is effective intermittently with the operation of the motor in cooperation with a continuously operating motive force.

It is still another object of the present invention to provide an improved stock quotation projecting machine in which the tape pulling effect and the vibration dissipating effect are produced by one and the same means in cooperation with a continuously operating motive force.

These and other features, capabilities and advantages of the invention will appear from the subjoined detail description of one specific embodiment thereof illustrated in the accompanying drawing in which

Figure 1 is a side elevation of a machine equipped according to the present invention;

Fig. 2 is a fragmental enlarged side elevation partly in section of a part of the control mechanism for the tape pulling device; and

Fig. 3 is a fragmental enlarged end elevation partly in section of a part of the control mechanism for the tape pulling device showing its connection with the rewind reel and the belt to the motor.

In the embodiment illustrated, there is shown the casing 1 of a ticker preferably of the high speed type from which the tape T passes across the light aperture formed on the extension 2 of the lamp housing 3. To facilitate movement of the tape T across the light aperture, there is preferably provided at the entrance end to the light aperture, a roller 4 and at the discharge end a roller 5.

From the light aperture, the tape passes down around the main tape puller, or tape pulling sheave 6 which is mounted on the shaft 7 extending through the casing 8 and journaled therein. The shaft 7 is operatively connected to the electric motor 9 by the driving connection now to be described.

On the shaft 7, there is fixed the worm wheel 10 which meshes with the worm 11 freely mounted on the shaft 12. The shaft 12 is also journaled in the casing 8 below the shaft 7 and disposed at right angles to the shaft 7 to transmit to the

shaft 7 and in turn to the tape puller 6, an angular movement with a different center of rotation and also with a different velocity than that of the shaft 12. On the shaft 12 and outside of the housing 8, there is fixed the pulley 13 which is connected by the belt 14 with the pulley 15 on the shaft 16 of the motor 9, which in the present instance is intended to continuously operate during the trading hours in which the machine is to be used and only interrupted at the end of the trading hours.

The shaft 12 inside of the casing 8 is provided with the discs 17 and 18 which are preferably fixed on the shaft 12 adjacent the bearings 19 and 20 to locate the shaft 12 in place. There is also fixed on the shaft 12, and to rotate therewith, a disc 21 which provides one of the clutch faces. The disc 21 is disposed adjacent to the worm 11 and the end of the worm 11, to wit the face 22 forms one of the clutch faces to engage the face 23 of the disc 21 forming the other clutch face. The face 22 of the worm 11 is normally maintained in frictional engagement with the face 23 of the disc 21 by the spring 24 which is tensed between the disc 17 and the collar 25 of the roller bearing ring 26, or thrust bearing, which collar 25 is spaced from the collar 27 of the ring 26 by the ball bearings 28. The collar 27 of this bearing ring 26 engages the left hand end of the worm 11 normally through the spring 24 to maintain the worm 11 in engagement with the disc 21.

The tape T is maintained in engagement with the pulling sheave 6 by the pressure roller 29 which is mounted on the end of the bracket 30 pivoted at 31 and provided with an adjustable weight 32. From the pulling sheave 6, the tape T passes up over the rewind reel 33 which is mounted on the shaft 34 journaled in the bearing 35 formed at the upper end of the arm 36 extending upwardly from the casing 8. The shaft 34 extends through the bearing 35 and has fixed thereon the sheave 37 which is connected by the belt 38 to the sheave 39 mounted on the shaft 7. The belt 38 is preferably composed of a yieldable substance such as a spring to facilitate slippage between the rewind reel and the shaft 7 which is particularly desirable as disclosed in this art due to the rewind reel increasing speed transmitted to the tape T caused by the increasing diameter of the paper roll being formed on the rewind reel in the course of rewinding.

The shaft 7 is operatively connected to the control arm 40 in the manner now to be described. The shaft 7 is provided with a pinion 41 in the

present instance fixed on the shaft 7 between the casing 8 and the sheave 39 and meshes with the small pinion 42 mounted on the stub shaft 43 extending from the side of the casing 8. The small 5 pinion 42 is preferably provided with a hub 44 containing ball bearings 45 for engaging the shaft 43 and which hub 44 forms with the wings 46 and 47 a butterfly.

The wings 46 and 47 are preferably composed of 10 a spring like resilient material and are connected to the hub 44 to extend tangentially therefrom and preferably formed on diametrically opposite sides of the hub 44. The butterfly formed by the wings 46 and 47 is adapted to cooperate with the 15 finger 48 of the control arm 40. This finger 48 is formed at the end of a bracket arm 49 pivotally mounted on the pin 50 extending from the arm 36.

The finger 48 as shown in Fig. 2 preferably is 20 provided with a tapered end 51, as indicated. The bracket arm 49 is preferably provided with a split tubular extension 52 to receive the end of a 25 rod 53. This tubular portion 52 is preferably provided with ears 54 for the reception of the screw 55 by means of which the split tubular extension 52 may securely anchor the rod 53 against displacement. The rod 53 of the control arm 40 30 preferably is bent upwardly at 56 to extend up to the bend 57 to one side and above the level of the light aperture from which bend the rod 53 extends 35 across the light aperture to the bend 58 where it extends downwardly to form the tape controlling finger 59 which may be a roller or the like.

The images formed of the characters or markings 35 on the tape at the light aperture on the extension 2 will pass up through the objective lens formed in the housing 60 supported in place above the light aperture by the bracket 61 extending upwardly from the housing 3. The images so received 40 by the objective lens in the housing 60 will then be directed onto the screen. In the present instance, such images will first strike the mirror 63, be reflected onto the mirror 62 and then finally appear on the screen 64, such screen 64 and mirrors 63 and 62 being generally connected to one 45 another to form what is known in the trade as the D housing.

From the foregoing, it will thus appear that 50 when the ticker operates the tape T discharging therefrom will be drawn across the light aperture on the extension 2 by the pulling sheave 6 and wound on the reel 33. The finger 59 engaging 55 the tape between the ticker and the light aperture will dissipate the vibrations transmitted thereto by the ticker, such finger 59 being formed 60 at the end of an extended control arm 40 which due to its weight and leverage will take up the slack formed in the tape as quickly as formed and consequently iron out the vibrations transmitted to the tape by the ticker. Furthermore, when 65 the ticker stops, the sheave 6 continuing to take up the tape will cause the loop formed under the finger 59 to be taken up and consequently the finger 48 to be depressed into the path of movement of the wings 46 and 47 of the butterfly.

As soon as the finger 48 engages one of the wings, for instance the wing 46, it will cause the 70 pinion 42 to come to rest, in turn anchoring the pinion 41 against rotation thereby to cause the sheave 6 to come to rest and thus discontinue the tape pulling action of such sheave 6. When such pinion 41 so comes to rest, it will of course also 75 cause the worm wheel 10 to come to rest and

react on the worm 11, the threads of which will cause the worm 11 to turn on the shaft 12 away from the disc 21 and in opposition to the spring 24 so that the clutch faces 22 and 23 will be separated and thus the worm 11 be free to stop with the worm wheel 10 while the shaft 12 will continue to be operated with the motor 9.

In turn when the ticker again starts operating, it will initially form a loop under the finger 59 and when this loop is large enough so that the 10 finger 59 in following it, causes the finger 48 to rise sufficiently to release the wing 46 or 47, the butterfly will of course be again free to operate and since there will constantly be an urge on the worm wheel 11 by the spring 24 to bring the 15 clutch faces 22 and 23 into engagement and also to cause the worm wheel 11 to rotate due to its large supporting surface on the shaft 12, the worm wheel 10, pinions 41 and 42 to pick up speed to 20 their normal speed so as to gradually cause the sheave 6 to come into normal tape pulling action again.

It is obvious that various changes and modifications may be made to the details of construction without departing from the general spirit of the invention as set forth in the appended 25 claims.

I claim:

1. A tape control mechanism including a tape 30 pulling sheave, a driven shaft for said sheave, an interrupting device operatively connected to said sheave, a lever responsive to the deflections in the tape mounted to rock about a horizontal axis parallel to said first named shaft and to control 35 said interrupting device, a worm wheel fixed to rotate with said sheave, a continuously operating drive shaft extending at right angles to said first named shaft, and a slippage device including a worm rotatably mounted on said drive shaft and in mesh with said worm wheel, and a collar fixed on said drive shaft to clutchingly engage said worm when said interrupting device is liberated and to slip relative to said worm when said interrupting device is arrested.

2. A tape control mechanism including a tape 40 pulling sheave, a driven shaft for said sheave, an interrupting device operatively connected to said sheave, a lever responsive to the deflections in the tape mounted to rock about a horizontal axis parallel to said first named shaft and to control 45 said interrupting device, a worm wheel fixed to rotate with said sheave, a continuously operating drive shaft extending at right angles to said first named shaft, and a slippage device including a worm rotatably mounted on said drive shaft and in mesh with said worm wheel, a collar fixed on said drive shaft, and a spring for urging 50 said worm into clutching engagement with said collar when said interrupting device is liberated and to yield to permit said collar to slip relative to said worm when said interrupting device is arrested.

3. A tape control mechanism including a tape 55 pulling sheave, a driven shaft for said sheave, an interrupting device operatively connected to said sheave, a lever responsive to the deflections in the tape mounted to rock about a horizontal axis parallel to said first named shaft and to control 60 said interrupting device, a worm wheel fixed to rotate with said sheave, a continuously operating drive shaft extending at right angles to said first named shaft, and a slip clutch device including a worm rotatably mounted on said drive shaft and in mesh with said worm wheel, a collar 65 fixed on said drive shaft, said worm urging said 70

worm wheel in the direction of said collar, and a spring for urging said worm into clutching engagement with said collar for causing said worm to be operated when said interrupting device is 5 liberated and to yield when said interrupting device is arrested in turn to arrest said worm wheel and thereby cause said worm to withdraw out of clutching engagement with said collar.

4. A tape control mechanism including a tape 10 pulling sheave, a driven shaft for said sheave, an interrupting device operatively connected to said sheave, a lever responsive to the deflections in the tape mounted to rock about a horizontal axis parallel to said first named shaft and to 15 control said interrupting device, a worm wheel fixed to rotate with said sheave, a continuously operating drive shaft extending at right angles to said first named shaft, and a slippage device including a worm rotatably mounted on said drive 20 shaft and in mesh with said worm wheel, a clutching collar fixed to said drive shaft, an abutment collar fixed to said drive shaft, a thrust bearing rotatably mounted on said drive shaft, and a spring tensed between said abutment collar 25 and said thrust bearing to urge said worm into clutching engagement with said clutching collar when said interrupting device is liberated.

5. A tape control mechanism including a tape 30 pulling sheave, an interrupting device including a hub, yieldable veins tangentially extending from said hub, a lever responsive to the deflections in the tape to engage the inner faces of the ends of said veins to interrupt the operation of said interrupting device, and a continuously operating 35 drive shaft yieldably connected to drive said sheave when said interrupting device is liberated.

6. A tape control mechanism including a tape 40 puller, an interrupting device including a hub and yieldable wings extending tangentially from said hub, a lever responsive to the deflections in the tape to engage the inner faces of the ends of said wings to interrupt the operation of said interrupting device, and a continuously operating 45 drive shaft yieldably connected to said tape puller to actuate said tape puller when said interrupting device is liberated.

7. A tape control mechanism including a tape 50 pulling sheave, a driven shaft for said sheave, a gear fixed to said shaft, a second shaft, a pinion 55 fixed on said second shaft and in mesh with said gear, a butterfly fixed to said second shaft and having yieldable veins, a pivotally mounted lever having the end of one arm engaging a tape and responsive to deflections therein as the tape is advanced or not and the end of its other arm disposed to enter the path of movement of said veins to interrupt the operation thereof, a worm wheel 60 fixed on said first named shaft, a continuously operating drive shaft, and a slippage device interposed between said drive shaft and said worm wheel including a worm freely rotatable on said drive shaft and in mesh with said worm wheel, a clutching collar fixed on said drive shaft, said worm urging said worm wheel in the direction of said collar, and a spring for urging said worm into clutching engagement with said clutching collar for causing said worm to be operated when said butterfly is liberated and to yield when said butterfly is arrested in turn to arrest said worm

wheel and thereby cause said worm to withdraw out of clutching engagement with said collar.

8. A tape control mechanism including a tape 5 pulling sheave, a driven shaft for said sheave, a butterfly fixed to rotate with said driven shaft and having veins, a pivotally mounted lever having the end of one arm engaging a tape and responsive to deflections therein as the tape is advanced or not and the end of its other arm disposed to enter the path of movement of said veins to interrupt the operation thereof, a worm wheel fixed on said driven shaft, a continuously operating drive shaft, and a slippage device interposed between said drive shaft and said worm wheel including a worm freely rotatable on said drive shaft and in mesh with said worm wheel, a clutching collar fixed on said drive shaft, said worm urging said worm wheel in the direction of said clutching collar, and a spring for urging said worm into clutching engagement with said clutching collar for causing said worm to be operated when said butterfly is liberated and to yield when said butterfly is arrested in turn to arrest said worm wheel and thereby cause said worm to withdraw out of clutching engagement with said collar.

9. A tape control mechanism consisting of a frame, a shaft journaled in said frame, a tape 30 pulling roller fixed on said shaft, a second shaft journaled in said frame and extending at right angles to said first mentioned shaft, a driven sheave fixed on said second shaft, an interrupting device operatively connected to said first mentioned shaft and rotatably mounted on said frame, a slip clutch device rotatably mounted on said second shaft and in constant operative connection with said first shaft, a spring for urging said slip clutch device into driving engagement with said second shaft but yieldable to enable said slip clutch device to slip relative to said second shaft when said first shaft is arrested, and a lever pivotally mounted on said frame and having one arm extending therefrom ready to engage the tape to be pulled and the other arm movable to engage said interrupting device to arrest the same and in turn the first shaft.

10. A removable tape control unit consisting of a frame, a shaft journaled in said frame, a tape 40 pulling roller fixed to said shaft, an interrupting device rotatably mounted on said frame and operatively connected to said shaft, a second shaft journaled in said frame and disposed at right angles to said first shaft, a driven sheave fixed to said second shaft, an abutment fixed on said second shaft, a slip clutch device rotatably mounted on said second shaft and in constant operative connection with said first shaft, a spring for urging said slip clutch device into driving engagement with said abutment but yieldable to clear said abutment when said first shaft is arrested, and a lever pivotally mounted on said frame and having one arm engaging the tape to be pulled and having another arm movable into arresting engagement with said interrupting device when said lever is deflected by the tape to be pulled in turn to arrest said first shaft and clear said slip clutch device from said abutment.

AUGUST D. EITZEN.
